UNITED STATES PATENT OFFICE.

CHARLES HOLMAN, OF NEW YORK, N. Y.

BUTTON FOR CUFFS.

SPECIFICATION forming part of Letters Patent No. 563,768, dated July 14, 1896.

Application filed June 18, 1895. Serial No. 553,195. (No model.)

To all whom it may concern:

Be it known that I, CHARLES HOLMAN, a citizen of the United States, and a resident of the city and county of New York, State of New York, have invented certain new and useful Improvements in Buttons for Cuffs and the Like, of which the following is a specification, reference being had to the accompanying drawings, forming a part hereof.

This invention relates to buttons or studs or other like devices for connecting the ends of cuffs or wristbands or for other similar purposes. Ordinarily buttons or studs of this character are of two different classes, the buttons of one class being adapted for use with straight cuffs, which overlap at their ends when in use, and those of the other class being adapted for use with link cuffs, the ends of which do not overlap, but are usually separated somewhat while being worn.

The object of this invention is to produce a button of the general character referred to which can be used either with straight cuffs or with link cuffs, or for other analogous purposes, and shall be better adapted for such purposes than the buttons heretofore devised for like purposes.

In the accompanying drawings, forming a part hereof, and to which reference is to be had, Figure 1 is a central section of one embodiment of my invention, the parts being in position for use with straight cuffs. Fig. 2 is a similar view of the same form, but with the parts in position for use with link cuffs. Fig. 3 is a section on the line $x-x$ of Fig. 2, the direction of sight being upward. Figs. 4 and 5 are central sections of still another form, the two views showing the parts in their different positions. Figs. 6 and 7 are similar views of a further modification.

As represented in the several figures of the drawings, the button comprises two parts or members, which for convenience may be designated as a head, as A, and as a foot, as B. As shown, the head and foot are of different sizes, but it will be understood that they may be related as to size as may be desired and may have any desired form or configuration. As will appear more clearly hereinafter, when reference is had to the several figures of the drawings, the two members of the button are connected by links which will permit the two

members or parts to be separated somewhat widely, as is usual in link buttons, and is capable of being collapsed or shortened, so that the two members may be brought into closer proximity and may be there held substantially in the relation which exists between two members of a button for straight cuffs, provision being also made, as will hereinafter appear, for holding or retaining the two members in such proximity and relation in so far as they may require to be so held according to the particular construction of the two members and of the intermediate connection.

Referring now more particularly to the several concrete embodiments of the invention which are shown in the accompanying drawings, it will be seen that the head and foot are loosely connected by links or an equivalent device, and are so formed and attached to the links as to permit the head and foot to be connected together closely to form a button for straight cuffs and to be disconnected to form a link button by a rotation or partial rotation of one with respect to the other, the head and foot being screw-threaded or equivalently formed.

The head or upper member A of the button is made hollow, as represented in Figs. 1 and 2, as well as in Figs. 4, 5, 6, and 7, and adapted to receive and conceal within it the loose or link connection which permits the limited separation of the two members and the free movement thereof. As shown in Figs. 1, 2, and 3, the two members are connected by two links, which are pivoted together. The extremity of one link is pivoted to the head A, and the extremity of the other link is likewise pivoted to the foot or member B, but with a swivel-joint, the link C for this purpose being pivoted to a rod or pin c', which passes freely through the foot or member B and is provided with a head c² to prevent its withdrawal therefrom. The under side a⁴ of the head A is slotted, as at a⁵, to permit the links c⁵ and c⁶ to be introduced within the head, and is also provided with a boss a⁶, which is formed for engagement with the shank of the foot or member B, the two parts being preferably screw-threaded for this purpose. The swivel-joint of the link c⁶, with the foot or member B, permits the necessary rotation of the one part or member with refer-

ence to the other in order to effect the engagement thereof, as represented in Fig. 1, in which position the two members are held rigidly together, the intermediate connection 5 which, when the parts are in the position shown in Fig. 2, permits the necessary free movement of the two members with respect to each other, being collapsed or extended as the case may be.

10 A form differing but slightly from that just described is shown in Figs. 4 and 5, in which the head A is hollow, as before, while its under side a^4 is provided with a boss a^6 for engagement with the shank of the foot or member 15 B. The links c^9 and c^{10} are represented as ordinary open links, the link c^9 engaging a ring c^{11} , which is of such diameter as to prevent its withdrawal through the aperture in the boss a^6 , while the link c^{10} is represented 20 as engaging a headed pin or rod c^7 , which swivels in the foot B. The swivel connection with the foot B is not essential, inasmuch as the free movement of the links and ring within the head A will permit the necessary rotation 25 of the one member with respect to the other which is required to effect their engagement. Another similar form is shown in Figs. 6 and 7, in which the hollow head or member A and

the foot or member B are shown as connected by a chain c^{12} , which at one end is secured to 30 a swivel-pin c^7 and at the other end to some form of take-up device within the head A, such as the spring c^{13} , which is attached at one end to the head A. A stop-ring c^{11} may be employed in connection with the chain c^{12} 35 to prevent excessive strain upon the spring.

I claim as my invention—

A button for cuffs and the like, the same comprising a head and a foot, the head being hollow and the under side of the head having 40 a central aperture and a screw-threaded boss surrounding the same, and links attached centrally to the inside of said head through said aperture and to said foot and connecting the same loosely, the links being adapted 45 to be received wholly within the hollow head through the aperture in the under side of said head, and the said foot having a screw-threaded shank to engage said boss, substantially as shown and described. 50

This specification signed and witnessed this 17th day of June, A. D. 1895.

CHARLES HOLMAN.
